UNITED STATES PATENT OFFICE

123,990

DESIGN FOR A DRESS

Augusta Waxberg, New York, N. Y.

Application October 23, 1940, Serial No. 96,018

Term of patent 3½ years

To all whom it may concern:

Be it known that I, Augusta Waxberg, a citizen of the United States, residing at 751 Walton Ave., New York city, in the county of Bronx and State of New York, have invented a new, original, and ornamental Design for a Dress, of which the following is a specification, reference being had to the accompanying drawing, forming part thereof.

I claim:

The ornamental design for a dress, substantially as shown.

AUGUSTA WAXBERG.
